UNITED STATES PATENT OFFICE.

DEMETRIUS KEMP, OF NEW YORK, N. Y., ASSIGNOR TO KEMP & BEATLEY, INC., OF NEW YORK, N. Y., A CORPORATION OF NEW YORK.

DESIGN FOR A BEDSPREAD.

Application filed December 9, 1926. Serial No 19,993. Term of patent 3½ years.

To all whom it may concern:

Be it known that I, DEMETRIUS KEMP, a citizen of the United States, residing in the city, county, and State of New York, have invented a new, original, and ornamental Design for a Bedspread, of which the following is a specification, reference being had to the accompanying drawings, forming part thereof.

Drawings:

The figure is a top view of a bedspread showing my ornamental design.

I claim:

The ornamental design for a bedspread as shown.

DEMETRIUS KEMP.
